LOCK

Theodore H. Johnstone, Detroit, Mich.

Application October 30, 1933, Serial No. 695,758

10 Claims. (Cl. 70—419)

My invention relates to locks but particularly to locks of the cylinder type in which a key rotatable cylinder has radially movable tumblers or wafers which variably project to normally lock the cylinder against rotation and which, by the insertion of the proper key, are withdrawn or brought into proper alignment to permit rotation of the cylinder.

With locks of this type the usual construction has been to provide a channel in the stationary case surrounding the cylinder into which channel the ends of the tumblers or wafers projected to lock the cylinder against rotation when the key was withdrawn. With this construction the lock may be readily picked by exerting rotary effort on the cylinder and then inserting suitable tools into the keyhole and shifting and cramming the tumblers or wafers, one at a time, into releasing position so that the cylinder could then be turned without need of the proper key.

The main object of my invention is to provide simple structure and operation for preventing such picking of the lock. In general the invention contemplates the elimination of the stationary locking slot for receiving the tumbler or wafer ends, and the insertion between the cylinder and the surrounding casing of a cylindrical floating sleeve or shell with a longitudinal slot therethrough for receiving the tumbler ends, which shell serves, when attempt is made to rotate the cylinder and pick the lock without the use of the proper key, to operate locking means which will lock the cylinder to the surrounding casing and thus prevent operation of the lock. Upon turning of the cylinder without the use of the proper key the projected tumblers will carry along the freely rotatable shell which can therefore afford no stationary surface against which the tumblers could be crammed or wedged during attempts to pick the lock, but, before the cylinder can be rotated far enough for unlocking movement of means to be controlled by the lock, the locking mechanism within the lock will be actuated by the sleeve to lock the cylinder to the stationary casing.

The various features and details of my invention are incorporated in the structures disclosed on the drawing, in which drawing

Figure 1 is a side elevation of a lock structure with a lock shaft extending therefrom;

Figure 2 is an enlarged plan view of the lock body with the outer stationary casing in horizontal diametral section;

Figure 3 is a side elevation with parts in vertical diametral section;

Figure 4 is a section on plane IV—IV of Figure 2;

Figure 5 is a section on plane V—V of Figure 2; and

Figure 6 is a developed view to more clearly illustrate the lock operation.

The lock structure shown comprises the tubular cylindrical casing 10 for surrounding and journaling the lock cylinder or barrel 11, the casing in practice being stationarily mounted in a suitable support. At its outer end the casing 10 receives a collar or bushing 12 rigidly secured therein and having the outer flange 12' for abutting the outer edge of the casing.

The lock cylinder or barrel 11 is cylindrical and has the neck 13 at its inner end of reduced diameter. At its outer end the cylinder has the head 14 abutting against the outer edge of the flange 12' of the collar 12, the cylinder at its outer end having bearing in the collar. At its inner end the reduced neck 13 of the cylinder has bearing in the internal lug 15 on the casing 10.

The lock cylinder shown has a longitudinal row of vertical diametrically extending passageways 15' for the tumbler wafers 16, a compression spring 17 being provided for each tumbler and seating in a niche 18 to abut against a lateral arm 19 of the respective tumbler so that normally the tumblers are projected variable distances beyond the periphery of the cylinder, the casing 10 being provided with circumferentially extending slots 20 for receiving the tumbler ends.

Between the casing 10 and the cylinder 11 is interposed a cylindrical shell or sleeve 21 which at its front end is concentric with and abuts the inner edge of the collar 12 and at its rear end abuts the bearing lug 15 so as to be confined against axial movement. This sleeve has the opening or slot 22 through which the tumbler ends extend when the key K is withdrawn from the cylinder. When the key designed for the lock is inserted into the keyhole 23 the tumblers are shifted radially to be entirely within the periphery of the cylinder so that the cylinder may then be turned relative to the casing 10. The sleeve 21 may also be provided with a slot 22' diametrically opposite the slot 22 in case a cylinder structure is used in which the tumblers normally project in opposite directions beyond the cylinder periphery when the key is withdrawn. With such tumbler arrangement the casing 10 has also a lower set of circumferential slots 20'. As shown the bushing 12 has upper and lower slots 24 and 24' registering with the first upper and lower slots in the

casing and registering also with the upper and lower slots 22 and 22' in the sleeve 21 when the lock is in normal position. The widths of the slots 22, 22' and 24, 24' are a trifle more than the widths of the tumbler wafers so that these wafers may readily move in and out under normal conditions without binding. With the arrangement thus far described, when attempt is made to turn the cylinder without the use of the proper key the outer tumbler 16' will abut against the slot in the stationary bushing 12 and turning of the cylinder will be prevented. In order therefore to turn the cylinder without the key this first tumbler must first be picked and moved inwardly out of the bushing slot or slots. However, if after withdrawing the first tumbler the cylinder is rotated the other projecting tumblers will engage against the side of the slots in the sleeve 21 and this sleeve will turn with the cylinder. This turning movement of the cylinder is utilized to actuate locking mechanism for positively locking the cylinder to the casing after a slight rotary movement of the sleeve with the cylinder. In the casing 10 are two longitudinally extending rectangular channels 25 and 25' in which rectangular pawls 26 and 26' are shiftable, these pawls being held in the channels by the neck 13 of the cylinder 11. Midway between the channels a pin 27 secured in the casing 10 pivots a walking beam 28 which at its end abuts 30 against the outer ends of the pawls, the walking beam being held in position by the neck 13 of the cylinder. With this arrangement, upon outward shift of one of the pawls, the other pawl will be shifted inwardly. At their inner ends and their 35 inner sides the pawls are cut away to provide the inclined surfaces or faces 29 and 29' respectively. At its inner end the sleeve 21 has notches 30 and 30' cut therein with which the inner ends of the pawls register, these notches having the inclined 40 sides or edges 31, 31' for cooperation with the beveled faces 29 and 29' of the pawls so that upon rotation of the sleeve 21 in either direction the corresponding pawl will be cammed outwardly, the walking beam will be rotated, and the other 45 pawl shifted inwardly.

Means are provided for normally yieldably holding the cylinder and the sleeve in normal position with the sleeve slots 22 in alignment with the tumbler passages. As shown, the outer end of the neck 13 of the cylinder is hollow to provide a cylindrical chamber 32 from which a bore 33 of reduced diameter extends through the front part of the neck 13. A transmission shaft or rod 34 extends a distance into the chamber 32 and has 55 the reduced end 35 for engaging in the bore 33, a pin 36 extending through the neck 13 and the shaft end 35 to secure the shaft to the neck and therefore the cylinder structure so that upon turning of the cylinder structure the shaft will be turned. 60 At the chamber 32 the neck 13 is cut away thus providing abutment edges or shoulders 37 and 38 which are in alignment with the lower edges of lugs 39 and 40 on the inside of the casing 10 and extending longitudinally. A coiled spring 41 is 65 received within the chamber 32 and surrounds the end 35 of the shaft 34, the ends 42 and 43 of the spring extending laterally to engage the respective shoulders 37 and 38 and the lugs 39 and 40. When the lock is in normal position the shoulders and lugs are in alignment as shown in Figure 4.

At the inner end of the cylinder 11 are locking notches 44 and 44' for cooperating with the ends of the pawls, each of these notches having an outer straight locking abutment edge or shoulder

45 and at its inner end the inclined face 46. In the normal position of the lock as shown in Figures 2 and 3 the notches 30 and 30' of the sleeve 21 are in alignment with the cylinder notches 44 and 44', the cylinder notches being smaller than the sleeve notches and the sleeve end projecting a distance beyond the cylinder 11 as plainly shown in Figure 6. In this normal position the pawls 26 and 26' have their inner ends in alignment with the inner end of the cylinder and their beveled faces in alignment with the beveled edges 31, 31' of the slots 30 and 30' as shown in Figures 2 and 3. If now the proper key be inserted in the keyhole the lock tumblers or wafers will be cammed in to release the cylinder for turning with the key and consequent turning of the shaft 34 for unlocking of mechanism to be controlled, the shaft 34 being shown as provided with a cam pin 47 for connection with a lock bolt or other locking means to be unlocked. During such legitimate turning of the lock cylinder the sleeve 21 and the pawl mechanism will remain at rest. Should, however, attempt be made to rotate the cylinder with any device or tool other than the proper key such rotation will be resisted by the outer lock tumbler 16' which projects through the slot in the stationary bushing 12. This tumbler would then have to be picked first before further rotative effort could be applied on the cylinder. However such rotation of the cylinder 30 would cause rotation therewith of the sleeve 21 engaged by the remaining projecting tumblers. Suppose this rotation effort is in the direction of the arrow indicated on Figures 2, 3, and 6. Immediately as the sleeve starts to rotate with the barrel the inclined or cam surface 31 on the sleeve will engage the beveled end of the pawl 26 and will shift this pawl outwardly (Figure 6), which causes rotation of the walking beam 28 and inward shift of the pawl 26' and as the cylinder rotates its locking notch 44' is brought into position to receive the end of the inwardly shifted pawl 26' and the straight face or abutment 45 of the notch 44' abuts the pawl and further rotation of the cylinder is prevented as the pawl locks the cylinder to the casing. This slight rotary movement of the sleeve locks the cylinder against further rotation so that the shaft 34 cannot be turned a sufficient distance to effect unlocking of the mechanism controlled by the lock. After locking of the cylinder by the pawl mechanism the entire rotational strain on the cylinder will be taken up by the pawl mechanism, and as the slots in the sleeve are wider than the slots in the cylinder, the sleeve after locking of the cylinder, will have considerable play and freedom in both directions of rotation so that the sleeve cannot be utilized as a means against which the tumblers could be crammed by the person attempting to pick the lock and picking is thus frustrated.

If the picker, being frustrated against rotating the cylinder in one direction, should attempt to rotate the cylinder in the opposite direction, the cam surface 31' on the sleeve will encounter the beveled surface of the pawl 26' and shift this pawl outwardly away from the cylinder but thereby causing inward shift of the other pawl 26 into the locking notch 44 of the cylinder and the cylinder will be again locked against further rotation. As soon as the picking tools are withdrawn the spring 41 will return the cylinder to its normal position and the projected tumblers will also rotate the sleeve 21 back to its normal position and during return of the cylinder to normal

position the respective cam face 46 on the cylinder will shift out the respective pawl to its unlocking position and return the pawl structure to normal position with the pawl ends out of the cylinder slots 44, 44' and with their beveled faces alongside of the respective cam surfaces 31 and 31' on the sleeve, and the lock will now be in condition for proper operation with the proper key.

10 I have shown a practical and efficient embodiment of the various features of my invention but I do not desire to be limited to the exact construction, arrangement and operation shown and described as changes and modifications may be 15 made without departing from the scope of the invention as outlined in the accompanying claims.

I claim as follows:

1. In a lock structure, the combination of a casing, a rotatable cylinder in said casing having radially extending locking tumblers, a sleeve within said casing surrounding said cylinder and having a slot for receiving the cylinder tumblers when projected, said sleeve being free to rotate by the engagement of the projected tumblers 25 therewith when the cylinder is rotated, and means separate from said sleeve and controlled during the initial part of such rotary movement of the sleeve with the cylinder to directly lock the cylinder against further rotational movement.

30 2. A lock structure comprising a casing, a cylinder rotatable in said casing and having radially projectable tumblers, a sleeve freely rotatable in said casing and surrounding said cylinder and having a slot for receiving the tumblers when 35 projected and by which said sleeve will be caused to rotate with said cylinder when the tumblers have not been withdrawn by the insertion in the cylinder of a proper key, a locking member separate from said sleeve and movably mounted 40 within said casing, and means controlled by the rotary movement of said sleeve with said cylinder for interlocking said locking member with said cylinder to prevent further rotational movement thereof.

45 3. In a lock structure of the class described, the combination of a casing, a cylinder rotatable within said casing and having radially moving tumblers normally projected therefrom, a sleeve rotatable within said casing and surrounding said cylinder and having a slot for receiving the projected tumblers, said tumblers being adapted 50 to be withdrawn from the sleeve slot by the insertion of a proper key in the cylinder whereafter said cylinder may be turned to operate the 55 lock without causing rotation of said sleeve, the projected tumblers causing rotation of the sleeve with the cylinder if attempt is made to rotate the cylinder without the proper key, a locking bolt shiftable on said casing, said cylinder having a 60 locking notch, and means controlled during the initial rotational movement of said sleeve with said cylinder to cause said locking bolt to be projected into said locking notch whereby to lock said cylinder to the casing against further rotational movement therein.

65 4. In lock structure of the class described, the combination of a casing, a cylinder rotatable in said casing and having shiftable tumblers with means tending normally to shift the tumblers 70 outwardly beyond the cylinder periphery, a shell rotatable within said casing and surrounding the cylinder and having a slot for receiving the ends of the projected tumblers whereby turning of said cylinder without withdrawal of the tumblers will 75 cause rotational movement of the sleeve with the

cylinder, said sleeve having a cam surface, said cylinder having a locking abutment, and locking mechanism on said casing engageable by said cam surface to be applied to said cylinder abutment when said sleeve rotates with the cylinder 5 whereby further rotational movement of the cylinder will be prevented.

5. In a lock, the combination of a casing, a lock cylinder in said casing having transverse passageways therethrough and locking tumblers 10 shiftable in said passageways to normally project beyond the ends thereof and to be withdrawn into the cylinder when the proper key is inserted in the cylinder, and structure intermediate said casing and cylinder and having passageways for 15 coinciding with opposite ends of said tumbler passageways to receive the ends of projected tumblers, said intermediate structure being movable with the projected tumblers upon turning of the cylinder whereby to retain the passageways 20 therein in alignment with the tumbler passageways, and means separate from said intermediate structure and controlled by the movement of said intermediate structure with the cylinder to directly lock the cylinder against further rotational 25 movement.

6. In a lock structure, the combination of a casing, a lock cylinder in said casing having tumbler passageways therethrough and locking tumblers shiftable in said passageways to project 30 therefrom at either end thereof, a freely circumferentially embracing movable element within said casing, means whereby said element will move with said cylinder when said cylinder is turned without retracting said tumblers, and 35 means separate from said movable element and controlled by the movement of said movable element to lock said cylinder against further movement after an initial movement of said element with said cylinder.

40 7. In a lock structure, the combination of a casing, a rotatable cylinder in said casing having transversely extending locking tumblers, a sleeve within said casing surrounding said cylinder and having a slot for receiving the locking 45 tumblers when projected, said sleeve being free to rotate with the cylinder by the engagement of the projected tumblers with the sleeve when the cylinder is rotated, and means separate from said sleeve and controlled during the initial part 50 of such rotary movement of the sleeve with the cylinder to directly lock the cylinder against further rotational movement.

55 8. In a lock structure, the combination of a casing, a lock member in said casing having passageways and locking tumblers shiftable in said passageways to project therefrom, a freely movable sleeve within said casing, means whereby said sleeve will move with said lock member when said lock member is moved without retracting said tumblers, and means separate from said sleeve and controlled by the movement of said movable element to lock said lock member against further movement after an initial movement of said movable sleeve with said lock member.

60 9. In a lock, a lock cylinder, tumblers carried by the lock cylinder and yieldably projected from the lock cylinder, a stationary mounting member to rotatably mount the cylinder, said stationary mounting member having recesses to receive the projected ends of the tumblers, said recesses being wider than the width of the tumblers to allow a predetermined degree of rotation on the part of the lock cylinder while the tumblers are in their projected locking positions, a movable member 70 75

having openings through which the tumblers project for engagement with the recesses of the stationary member, said openings being narrower than the recesses so that the edges thereof are near the tumblers to be engaged by the tumblers upon turning of the lock cylinder while the tumblers are projected so that said edges move with the cylinder and the tumblers to retain their relative positions with respect to the tumblers and prevent decoding by bringing the tumblers to bear against the corner of any one of said edges, and means separate from said sleeve and to positively interlock said lock cylinder and stationary mounting member upon rotation of the cylinder effected while the tumblers are projected prior to

the tumblers reaching the edges of the recesses in the stationary mounting member.

10. In a locking structure, the combination of a casing, a rotatable cylinder in said casing having radially extending locking tumblers, a sleeve within said casing surrounding said cylinder and having a slot for receiving the cylinder tumblers when projected, said sleeve being free to rotate by the engagement of the projected tumblers therewith when the cylinder is rotated, and means movable relative to said sleeve and controlled during the initial part of said rotary movement with the cylinder to directly lock the cylinder against further rotational movement.

THEODORE H. JOHNSTONE. 15
